UNITED STATES PATENT OFFICE.

MICHAEL VOGELSONG, OF TOLEDO, OHIO.

WIRE-COILING APPARATUS.

1,394,378.

Specification of Letters Patent.

Patented Oct. 18, 1921.

Application filed July 21, 1920. Serial No. 397,943.

To all whom it may concern:

Be it known that I, MICHAEL VOGELSONG, a citizen of the United States of America, residing at Toledo, Lucas county, Ohio, have 5 invented new and useful Wire-Coiling Apparatus, of which the following is a specification.

This invention relates to the forming of wire.

10 This invention has utility in the winding of wire into conical or pyramidal sections, as for gas flame heated toasters.

Referring to the drawings:

Figure 1 is a fragmentary plan view of 15 an embodiment of the invention in forming Davy screen for gas flame bread toasters;

Fig. 2 is a side elevation, parts being broken away, of the apparatus of Fig. 1;

Fig. 3 is a detail view of the mandrel;

20 Fig. 4 is an enlarged plan view of a portion of the draw head;

Fig. 5 is a view of the toaster;

Fig. 6 is a fragmentary section on the line VI—VI, Fig. 2;

25 Fig. 7 is an enlarged plan view, with parts broken away, showing the draw head mounting;

Fig. 8 is an enlarged side elevation of the mounting of Fig. 7;

30 Fig. 9 is an end elevation looking into the draw head; and

Fig. 10 is a side elevation of the coil former.

A frame 1 is provided on which is disposed horizontally extending driving shaft 2 having a spline 3 along which is reciprocable clutch collar 4 as shifted by lever 5. This clutch member 4 may connect the shaft 2 for driving sleeve 6 extending through 35 bearing 7 on the frame 1, to mandrel 8. In the instance of forming Davy screen cones for toasters, the mandrel 8 is made multi-cornered, the showing herein being hexagonal. In setting up the wire screens, the 40 frusto-pyramidal coil is twisted to stagger the corners thereby increasing or giving approximate uniformity to the screen effect.

The mandrel 8 has converging end transverse terminus 9 with a groove or notch 10 thereacross as a partial wire seat. Carried by the frame 1 is a supplemental frame 11, having an overhanging bracket 12 with a lateral notch or seat 13, therein. Also carried by the frame 1, and on the opposite side 45 of the mandrel 8 from the frame 11 and bracket 12, is a bracket 14, carrying pivot

pin 15 for swinging handle 16 which may move into seating relation with the notch 13 of the bracket 12, and when so positioned, this handle 16 has a disk portion 17 against 60 the end or face 9 of the mandrel 8, completing the wire seat 10.

At a convenient location, the frame 1 may carry a reel 18 for a coil 19 of wire, which in the instance of these toaster screens is 65 desirably a rather hard No. 16 gage stock.

From the spool roll or coil 19, the wire 20 may pass by way of a fixed guide 21. Herein on this guide 21 is mounted a bracket 22 carrying freely movable horizontally extending arm 23. This swingable arm 23 has its free end forked into branches 24. A block 25 rigidly between the branches 24, imparts rigidity thereto, while way 26 through the block 25 may guide the wire 70 20 off the guide disk 21 from under the arm 23.

The free ends of these branches 24 are further reinforced by right and left threaded element 27 having medially enlarged portion 28 of polygonal form for adjustment. The positions of adjustment of this member 27, 28, in operation, must be such as to have opening 29, through the portion 28 aline with the opening 26, for the wire 20 to 80 85 thread therethrough. When adjusted, lock nuts 30, on the member 27, may be set up, and thus give fixedly held position to all the parts adjusted.

The branches 24, beyond this adjustable 90 reinforcement have forks 31 carrying pins 32 upon which are mounted for free rotation draw head wire gripping rollers 33 having central ways or grooves 34 to engage the wire 20.

95 In operation, when a coil of wire is wound upon the mandrel 8 to the gage mark 35, clutch lever 5 is thrown to stop the mandrel 8, the wire is cut, and the handle 16 pulled out of the seat or notch 13. The tendency of the coil to tighten on itself and slide down the tapered mandrel toward the small end, is at once availed of, for the seat 10 is open, and cross end 26 of the coil initially threaded into the complete seat 10, 17, may now 100 snap away from the mandrel and the whole coil is easily slipped off the mandrel. The operator at once swings the seat completing member or handle 16, back into the notch 13. In cutting the wire from the completed 105 coil, this is desirably done with at least one bend from a mandrel corner in the portion 110

of the wire severed from the coil. This partially bent section permits of very readily threading into the seat 10, 17, as the arm 23 is swung toward the small or starting end 5 of the mandrel 8. At once the bent end of the wire is in the seat 10, 17, the clutch 4 may be thrown in, and the winding operation repeated. As the arm 23 is freely swingable, it automatically follows along 10 the mandrel 8 as the one layer or coil is shaped up thereon. The speed may be quite high, in fact, so that with a little practice an operator may turn out three to four completed coils per minute. The drag in so tensioning the wire as to hold it snugly for 15 straight line directions between the mandrel corners, with the hard wire used, means the adjustment of the draw head places quite a load upon the mandrel 8. The adjustment 20 of the device 27, 28, may regulate this draw or tension.

The completed coils 36, as shown in Fig. 5, are assembled centrally of a bread slice holding frame 37.

25 The holding of the feed wire by the draw-head is not only a drag on the draw or pull of the mandrel in forming the coil, to insure that such coil is uniformly and firmly wound, but is a positive holder for the wire 30 when the strand is cut for removing a coil from the mandrel. This means that in high speed operation, the momentum of the unwinding from the reel may not crowd or buckle up and disturb any wire cut from the 35 coil, as the head holds such wire firmly as to the portion of the wire projecting from the head so that there may conveniently be great speed in threading the cut-off bent portion into the seat 10 as closed by the disk 17. 40 As this disk 17 extends fully across the face of the mandrel 8, the tight winding of the first wrap of the coil and the series thereafter, do not crowd off or down upon one side of the mandrel or over the mandrel end, 45 and are all held for compact symmetry as is essential for uniform product to be assembled into the toaster.

What is claimed and it is desired to secure by Letters Patent is:

50 1. A rotary multi-cornered tapered mandrel provided with a wire engaging seat

transversely of the end of the mandrel at the tapered region thereof, and a member coacting during mandrel rotation for holding a wire in said seat, said member being 55 movable as to the seat for freeing wire therefrom.

2. A rotary tapered mandrel provided with a wire engaging seat transversely of the converging end of the mandrel and 60 within the length of said mandrel, and a member entirely beyond the mandrel and entirely beyond any winding extent of the wire to be wound during winding thereof, 65 said member being movable as to the mandrel for holding the wire to be wound in said seat and said member being movable axially to clear the mandrel in allowing a mandrel formed coil freely to slip off the mandrel.

3. A terminally notched wire coiling 70 polygonal mandrel, and a member movable against said notch to complete a wire holding seat in said mandrel during wire coiling thereon, said member moving up only to a 75 flush position with the mandrel in allowing the coil formed on the mandrel to crowd thereagainst.

4. A terminally notched wire coiling rotary mandrel, a handle movable against the mandrel end as a coil receiving abutment to 80 complete a wire holding seat in the mandrel, and a draw head for directing wire to coil on said mandrel, said coil extending from adjacent said seat.

5. A wire coiling mandrel, and a draw 85 head for directing wire thereto including a swingable arm, a guide, and in alignment with the guide adjustable wire gripping means carried by the arm.

6. A multi-cornered tapered mandrel, and 90 a draw head for directing wire thereto including a swingable arm and a pair of adjustable grooved rollers carried by the arm.

7. A wire coiling mandrel of pyramid frustum form, and a draw head for directing 95 wire thereto including a swingable arm terminating at its free end in a fork, adjusting means for positioning the forks as to each other, and wire gripping grooved rollers carried by the fork.

In witness whereof I affix my signature.
MICHAEL VOGELSONG.
